ATTORNEY

UNITED STATES PATENT OFFICE.

WILLIAM A. LAUGHERY, OF STOCKTON, CALIFORNIA.

AUTOMATIC PRESSURE-ACTUATED GRAVITY OILER.

Application filed July 7, 1928. Serial No. 120,913.

This invention relates to improvements in gravity oilers for pressure water pumping systems, and is particularly intended for use in connection with a deep well pump apparatus which includes a turbine in the well and a drive means mounted in connection with the discharge head of the well casing directly above the well.

In apparatus of this character the oil is fed to the pump by gravity from above ground and a form of oiler commonly used is of the manually controlled sight feed type. With this type of oiler the attendant must close the oiler every time the pump is stopped, as otherwise the oil will continue to flow and a considerable waste will of course be had.

Automatically operated oilers are also on the market, including one operated by electricity, a mechanically operated one, and one known as the velocity type which also requires power for its operation. All such devices using up power, they cost the consumer something to run and these devices are somewhat complicated and expensive.

The principal object of my invention is to produce an automatic oiler for the purpose arranged to be operated by the water pressure generated with the operation of the pump, and as such pressure is created and is available whenever and only when the pump is operated, no power is used in operating the oiler, and there is no cost to the user other than the initial cost of the device itself.

A further object of the invention is to provide a device for the purpose which may be readily installed in connection with a standard pump drive unit.

Another object is to provide means for enabling the amount of oil fed from the oiler to be easily regulated while operating with a constant pressure and without interfering with the functioning of such pressure.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views.

Fig. 1 is a side outline of the discharge head and driving unit of a deep well pump

system showing my oiler installed in connection therewith.

Fig. 2 is an enlarged longitudinal section of the oiler taken on the line 2-2 of Fig. 1.

Referring now more particularly to the characters of reference on the drawings, the pump driving structure to which my oiler is applied includes a discharge head 1 through which the water under pressure passes, a tubular support or standard 1^a projecting upwardly from the discharge head and a driving motor 2 mounted on said standard. The motor has a shaft 3 depending therefrom to the pump below and enclosed in a sleeve 4 having a cap 5 on its upper end. Projecting outwardly from the cap is an oil pipe 6 to which the oiler of whatever character is employed is attached.

My oiling device, to be connected to said pipe 6, comprises a body 7 preferably of rectangular form and of suitable capacity. The body is adapted to be supported a short distance above the pipe 6 and outside the standard 1^a by means of brackets 8 attached to and projecting upwardly from said standard, 80 the body at its ends having feet 9 to rest on and be secured to said brackets.

Projecting upwardly through the body is a tube 10 having an enlarged head 11 on its lower end to engage a gasket 12 placed against the bottom of the body. A nut 13 is threaded on the top of the tube above the body to draw the head 11 snugly against its gasket. If desired or found necessary a spacer sleeve 14 may be placed about the tube 10 between the opposite faces of the body to prevent inward deflection of the body walls when the nut 13 is tightened up. The sleeve and tube adjacent the bottom of the body have radial and registering openings 15 leading from the body to the interior of the tube.

The member 10 adjacent its lower end and below the openings 15 is formed with an upwardly facing valve seat 16 to cooperate with pressure means for moving the lever in a valve opening direction, a glass tube 21 being fitted to the inside of the element 20 in any suitable and leak proof manner. This provides a sight feed arrangement enabling the oil dropping from the tube 10 to be readily seen. The lower end of the element 20 is tapped as at 22 to receive the upwardly projecting nipple 23 which is secured to the outer end of the oil pipe 6.

The pressure actuated means for operating

- the stem 17 comprises an enclosed casing 24 mounted at one end of the body. Extending across and secured to the casing in clearance relation to the front and back of the same is 5 a diaphragm 25 of suitable material, preferably a composition of rubber and canvas. The casing outwardly of the diaphragm is arranged for connection to the upper end of a pressure pipe 26 which at its lower end is 10 connected to the discharge head 1 so as to receive water under pressure passing through the head.

From the face of the diaphragm opposite to the pipe 26 a centrally disposed pin 27 15 projects outwardly through the adjacent face of the casing for engagement with one end of a lever 28 pivoted intermediate its ends onto said casing. The arm of the lever engaged by the pin passes between the casing 20 and the body 7; the other arm beyond the pivot extending over the body 7 for a certain distance, being then bent upwardly and finally horizontally toward the stem 17. At such end the lever is forked as at 29 for engagement 25 with a grooved sleeve 30 slidably mounted on the stem 17 above the cap 18. A normally slack stiff compression spring 31 is mounted on the stem above said sleeve, one end of the spring bearing against the sleeve and the 30 other end against a collar 32 fixed on the upper end of the stem. The stem 17 also has a collar 33 fixed thereon between the sleeve 30 and the cap 18 and another fixed collar 34 below the cap.

35 Formed with the casing 24 and overhanging the upper portion of the lever 28 is a bracket 35 in which is mounted an adjustable screw 36 to engage said lever; a compression spring 37 being disposed about said screw and bearing against the bracket and lever.

In operation when the pump is idle and no water under pressure is passing through the head 1 and pipe 6 the diaphragm is relaxed and the spring 37 acts on the lever 28 to force 45 the diaphragm outwardly or toward the pipe 26 and also to force the sleeve 30 against the collar 33, depressing the stem 17 and closing the valve. No oil then passes through the body. When the pump is driven and water 50 is passing through the head 1 and pipe 6, the diaphragm is acted on by the water and the lever is acted on to cause the resistance of the spring 37 to be overcome and the collar 30 to be raised, until the lever abuts against the 55 limiting screw 36. Raising of the sleeve 30 acts through the spring 31 and collar 32 to lift the needle valve off its seat, allowing the oil to flow from the body by gravity. The extent of opening of the stem irrespective of 60 the movement of the lever 28, is governed by adjustment of the cap 18 which limits the upward movement of the stem by reason of the collar 34 abutting against the cap after a certain amount of upward movement of the 65 valve stem has taken place. At the same

time further movement of the lever and sleeve 30 can be had without straining any part by reason of the compression of the spring 31 which then takes place after the stem becomes immovable. The movement of the diaphragm and the consequent movement of the lever is independently governed and limited by adjustment of the screw 36.

The amount of oil in the tank is visible 75 at any time by reason of a gage tube 38 mounted in the same in any suitable manner, the tank being filled when necessary upon the removal of a plug 39 on the top of the body.

From the foregoing description it will be 80 readily seen that I have produced such a device as substantially fulfills the objects of the invention as set forth herein.

While this specification sets forth in detail the present and preferred construction 85 of the device, still in practice such deviations from such detail may be resorted to as do not form a departure from the spirit of the invention, as defined by the appended claims.

Having thus described my invention what I claim as new and useful and desire to secure 90 by Letters Patent is:

1. A control device for the outlet of a gravity oiler comprising a valve stem to close the outlet, a tube in which said stem is slidable, an adjustable cap on the outer end of the tube, a collar on the stem inwardly of the cap and adapted to abut thereagainst when the valve has been opened a predetermined amount, a lever, connection means between one end of the lever and the stem outwardly 100 of the cap, and pressure actuated means applied to the lever to cause the same to then move the stem in a valve opening direction.

2. A control device for the outlet of a gravity oiler comprising a valve stem to close the outlet, an adjustable cap about the stem, a collar on the stem inwardly of the cap and adapted to abut thereagainst when the valve has been opened a predetermined amount, a lever, connection means between one end of the lever and the stem, pressure actuated means applied to the lever to cause the same to then move the stem in a valve opening direction, and means incorporated with said connection means for enabling further movement of the lever to take place after the collar has engaged the cap.

3. A control device for the outlet of a gravity oiler comprising a valve stem to close the outlet, an adjustable cap about the stem, a collar on the stem inwardly of the cap and adapted to abut thereagainst when the valve has been opened a predetermined amount, a lever, connection means between one end of the lever and the stem, pressure actuated means applied to the lever to cause the same to then move the stem in a valve opening direction, means incorporated with said connection means for enabling further movement of the lever to take place after the col-

lar has engaged the cap, and means for limiting such further movement of the lever.

4. A control device for the outlet of a gravity oiler comprising a valve stem to close the outlet, an adjustable cap about the stem a collar on the stem inwardly of the cap and adapted to abut thereagainst when the valve has been opened a predetermined amount, a lever, connection means between one end of the lever and the stem, pressure actuated means applied to the lever to cause the same to then move the stem in a valve opening direction, and spring means acting on the lever to move the same in the opposite direction.
5. A control device for the outlet of a gravity oiler comprising a valve stem to close the outlet, an adjustable cap about the stem, a collar on the stem inwardly of the cap and adapted to abut thereagainst when the valve has been opened a predetermined amount, a lever, a sleeve slidable on the stem and engaged by one end of the lever, pressure ac-

tuated means applied to the lever to cause the same to then move the stem in a valve opening direction, spring means acting on the lever to move the same in the opposite direction, and a collar on the stem between the cap and sleeve and adapted to be engaged by the sleeve when the said spring means is free to act.

6. A control device for the outlet of a gravity oiler comprising a valve stem to close the outlet, spaced collars on the stem, a member longitudinally adjustable relative to the stem projecting between the collars to be engaged thereby, a sleeve slidable on the stem above the collars, a compression spring about the stem above the sleeve, a stop on top of the stem above the spring and engaged thereby, and a pressure actuated lever engaging the sleeve.

In testimony whereof I affix my signature.

WILLIAM A. LAUGHERY.
